G. KRAUSE

FOOT SUPPORT

Filed July 11, 1921

UNITED STATES PATENT OFFICE.

GUSTAV KRAUSE, OF SCHNEIDEMUHL, GERMANY.

FOOT SUPPORT.

Application filed July 11, 1921, Serial No. 483,826, and in Germany February 11, 1916.

(GRANTED UNDER THE PROVISIONS OF THE ACT OF MARCH 3, 1921, 41 STAT. L., 1313.)

The object of this invention is to obviate the numerous injurious consequences, such as flat-feet, corns, calloused skin, formation of blisters, and the like, caused by certain 5 irregularities in the soles of boots or shoes. The invention is based upon the fact that endeavors made up to the present to produce boots and shoes which exactly fit the feet of the wearer for which they are intended 10 have been unsuccessful because the form of the boot or shoe has been determined from the foot while at rest. There are material differences, however, between a foot at rest, which supports no load, a resting foot which 15 supports a load, a moving foot which supports no load and a moving foot which supports a load. At the moment when the load is greatest the sole of a moving foot has between the heel and the ball, a trough-shaped 20 cavity, the length of which is about four times as great as its breadth and which lies approximately in the middle of the foot. The principal object of the present invention resides in constructing or shaping the inner 25 sole of boots and shoes with respect to the above mentioned cavity in the sole of the foot.

In order to make the invention more clear, reference is made to the accompanying drawings, in which Figure 1 is a perspective 30 illustration of a human foot showing the sole of the foot;

Figure 2 is a vertical transverse section through the lower portion of a human foot whilst in motion, showing the cavity in the 35 sole;

Figure 3 is a plan of two superposed soles for boots and shoes, viz, the outer sole and the inner sole;

Fig. 4 is a plan view of a last over which 40 the shoe is formed;

Fig. 5 is a longitudinal section taken on line V—V of Fig. 3 showing the inner and outer soles between which the inserted supplemental support is disposed;

Figure 6 is a vertical transverse section taken on line VI—VI of Fig. 3 through the two soles and the last at the portion where the cavity in the sole of the foot is greatest.

The object of the invention, therefore, is 50 to fill the above-mentioned cavity and to fully support the foot especially in that moment when the depth of the cavity is greatest, whereby the loaded foot is prevented from being straightened, making the cavity disappear. It is not only not injurious, but, to

the contrary, very useful that the support filling the said cavity exist also in the sole of a resting loaded foot, whereby the toes and the balls of the foot are constantly relieved from the pressure exerted by the load, 60 provided the filling member or insertion be made to correctly fit the general contour of the sole and its trough-shaped cavity in particular.

I am aware of the fact that insertions for 65 boots and shoes have already been recommended in order to diminish the annoyances brought about from any of the troubles mentioned above, but said insertions have never been manufactured with consideration of the 70 particular shape of the cavity in the sole of the foot, since, owing to incorrect shape, they do not fulfil their purpose and remain permanently at the proper position in the boot or shoe. The effectiveness of the insertion depends not so much on whether it is attached 75 to the inner sole so as to project upwards into the boot or shoe, but that the insertion should be arranged between the inner sole and the outer sole in a fixed position at the foot joint, 80 and this should be done with the aid of a last having a corresponding cavity in it and adapted to receive the insertion. To the last is applied first the inner sole, then the insertion, and then the outer sole which is connected 85 with the inner one by stitches, nails, and adhesive, or by any other means.

In order to give the inner sole the proper convex shape in its grained surface at the portion of the last provided with the cavity, 90 the inner sole and the outer sole are so dimensioned as to have in the finished boot or shoe about the same breadth at that point where the cavity is greatest (Figure 6), whereas the usual manner is to let the outer 95 sole project on both sides by about $\frac{1}{2}$ centimeter over the inner one. The proper dimension in the sense of this invention is that the outer sole is, adjacent the cavity, slightly smaller than is customary with boots or shoes 100 of the respective size, whereas the inner sole is, at the place in question, a little broader.

Figure 3 shows the inner sole 2 in its normal position upon the outer sole of an ordinary boot or shoe.

The last shown in Figure 4 corresponds 105 to the sole shown in Figure 3. The last 4 has a cavity 5 which corresponds to the portion 3 of Figure 4 and the depth of which amounts to from 3 to 4 millimeters. Figure 110

6 shows the parts in their proper relative position together with, and upon, the last, 4 being the last, 2 the inner sole, 3 the insertion, preferably of leather, 6 the upper of the boot or shoe, 1 the outer sole, and 7 a filling mass, preferably a mixture of cork powder and a binder, located between the sole 1 and the insertion 3.

Construction the sole portion of the shoe 10 in the described manner does not only obviate injury to the foot, but also to the boot or shoe. Due to the fact that the shape of the moving foot differs from the shape of the boot or shoe, the latter, if of the ordinary construction, is 15 subjected to strains which tend to change its shape. Such change of shape cannot take place, however, by reason of the substantially rigid construction of an ordinary boot or shoe, and the proper shape cannot, therefore, 20 be obtained merely by wearing that boot or shoe. The only effect is that additional strains are placed on the material, especially at the cavity in the sole (portion between A and B, Fig. 4), and at the toes and the balls, 25 the result being premature wear and tear of the boot or shoe. These additional strains do not exist in the present improved boot and shoe, its life being therefore lengthened, thereby effecting a saving in leather.

30 It follows that a boot constructed according to the above described principle fully supports the foot and strengthens it while loaded.

Having now described my invention, what I desire to secure by a patent of the United States is:

1. A boot or shoe comprising in combina-

tion with its outer parts, an inner sole, an upwardly bulged middle portion formed in said inner sole, said portion having such a configuration and position with respect to the sole as to be adapted to support the arch of the human foot and to correctly fill a cavity formed thereat while the wearer is walking, said portion extending forwardly from the heel longitudinally of the foot approximately 45 to the middle of the sole, a substantially inelastic insertion corresponding to the shape of said portion extending lengthwise and under a portion of the inner sole, and an outer sole holding said insertion permanently upon 50 said inner sole at that portion of the foot where the cavity is formed.

2. A boot or shoe comprising in combination with its outer parts, an inner sole, an upwardly bulged middle portion formed in said 55 inner sole, said portion having such a configuration and position with respect to the sole as to be adapted to support the arch of the human foot and to correctly fill a cavity formed thereat while the wearer is walking, 60 said portion extending forwardly from the heel longitudinally of the foot approximately to the middle of the sole, a substantially inelastic insertion corresponding to the shape of said portion extending lengthwise under 65 a portion of the inner sole, a filling material, and an outer sole holding said insertion and said filling material permanently upon said inner sole at that portion of the foot where the cavity is formed.

In testimony whereof I affix my signature.
GUSTAV KRAUSE.
